UNITED STATES PATENT OFFICE.

PREDA A. EFTOFIE, OF CHICAGO, ILLINOIS.

LOOSE-LEAF BINDER.

No. 800,482.

Specification of Letters Patent.

Patented Sept. 26, 1905.

Application filed October 14, 1904. Serial No. 228,421.

To all whom it may concern:

Be it known that I, PREDA A. EFTOFIE, a subject of the King of Roumania, residing at Chicago, in the county of Cook and State of Illinois, have invented certain new and useful Improvements in Loose-Leaf Binders, of which the following is a specification.

This invention relates to improvements in that class of binders employed for holding together in a compact and book-like form a number of loose leaves or sheets; and it consists in certain peculiarities of the construction, novel arrangement, and operation of the various parts thereof, as will be hereinafter more fully set forth and specifically claimed.

The principal object of the invention is to provide a binder of the above-named character which shall be simple and inexpensive in construction, strong and durable, and so made that the leaves may be quickly secured in place therein or readily removed therefrom.

Another object of the invention is to so construct the device that the back thereof will be held closely and firmly to the back edges 25 of the leaves and on one side thereof near their rear portions and will permit of the movement of the cover, so as to open the device like a book without exposing the rear edges of the leaves.

Other objects and advantages of the invention will be disclosed in the subjoined description and explanation.

In order to enable others skilled in the art to which my invention pertains to make and 35 use the same, I will now proceed to describe it, referring to the accompanying drawings, in which—

Figure 1 is a perspective view of a binder embodying my invention, showing the covers 40 thereof closed and a number of leaves in their bound positions. Fig. 2 is a perspective view of the blank out of which the back of the binder is formed. Fig. 3 is a fragmental perspective view of a portion of the back of the 45 binder, showing it by full lines in its completed form and by dotted lines before the blank is bent. Fig. 4 is a fragmental perspective view, partly in section, of the binder, showing one of the covers thereof raised. Fig. 5 is a longitudinal sectional view taken 50 on line 5 5 of Fig. 4 looking in the direction indicated by the arrows and showing one of the fasteners for holding the leaves in posi-

tion. Fig. 6 is a fragmental view of the rear portion of one of the leaves, and Fig. 7 is a 55 detached view of one of the washers or retaining-plates used in connection with the fasteners.

Like numerals of reference refer to corresponding parts throughout the different views 60 of the drawings.

The reference-numerals 10 and 11 represent the covers of the binder, each of which comprises a board 12, covered on each of its sides with a sheet 13, of cloth, leather, or other 65 suitable material, which sheets connect the boards 12 together at their back or adjacent edges, yet at a sufficient distance apart to permit of the insertion of the back of the binder between the inner and outer sheets 13 and between the adjacent edges thereof, as is clearly shown in Fig. 4 of the drawings. The back is formed out of a flat piece of metal 14, which is bent longitudinally at about its middle to form two sides 15 and 16 of a rectangle, the 70 lower side or flange 16 being provided near each of its ends with an opening 17 for the reception of fasteners for the loose leaves or sheets to be bound. The lower or outer surface of the side 16 of the back has located 75 thereon a piece of cardboard 18, which is interposed between said side and the outer sheet 13 of the covers. This piece 18 is employed to reinforce the side 16, as well as to form a slightly-yielding seat for each of the heads 19 80 of the fasteners which hold the sheets or leaves 20 in position. The fasteners are formed of two pieces 21 of ductile metal, and said pieces are normally located parallel and in juxtaposition with one another and have at one of 85 their ends a head 19, as is clearly shown in Fig. 5 of the drawings.

The rear portion of each of the leaves 20 to be bound is preferably provided with a reinforcing-strip 22 of any suitable material, each 95 of which strips have openings 23 to register with the openings 17 in one of the sides of the back of the binder.

By placing the binder so that its parts will assume the positions shown in Fig. 4 of the 100 drawings it is apparent that the side 15 of the back will occupy a vertical position, while the side 16 thereof will occupy a horizontal position. By placing the leaves 20 on the cover 11 and side 16 of the back, so that the 105 openings 23 in the reinforcing-strips 22 will

register with the openings 17, it is evident that the parallel pieces 21 of the fasteners may be passed through said openings until the heads 19 of the fasteners rest on the outer surface of the side 16 and reinforcing-strip 18, after which the free ends of the pieces 21 may be bent down, as shown in Figs. 4 and 5 of the drawings, so as to firmly hold the leaves 20 in position. In order to more securely fasten the leaves 20, a washer 25, having an opening 24 for the reception of the pieces 21 of the fastener, may be employed to rest between the reinforcing-strip 22 on the outer sheet 20 and the laterally-bent ends of each fastener.

By employing the above construction it is obvious that the covers 10 and 11 are hinged at the longitudinal edges of the back of the binder, so that the back edges of the leaves 20 will rest against one of the sides of the back and will not be disclosed or exposed when the covers are raised or opened.

Having thus fully described my invention, what I claim as new, and desire to secure by Letters Patent, is—

In a loose-leaf binder, the combination with two covers, of a flexible sheet secured to the outer and inner surfaces thereof so as to connect their back edges, an angular back located between said edges of the covers and also between said sheets, the said back having openings in one of its sides, a reinforcing-piece located on the outer surface of the apertured side of the back and having openings to register with its openings, a fastener comprising two parallel pieces extending through said openings and having a head on one of their ends and their other ends adapted to be bent laterally, substantially as described.

PREDA A. EFTOFIE.
